UNITED STATES PATENT OFFICE.

MAX ARNDT, OF AIX-LA-CHAPELLE, GERMANY.

APPARATUS FOR TESTING AIR OR OTHER GASES.

1,044,969.

Specification of Letters Patent.

Patented Nov. 19, 1912.

Application filed November 18, 1910. Serial No. 593,093.

To all whom it may concern:

Be it known that I, MAX ARNDT, a subject of the German Emperor, residing at the city of Aix-la-Chapelle, in the Kingdom of Prussia, German Empire, have invented certain new and useful Improvements in Apparatus for Testing Air or other Gases; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part of 15 this specification.

My invention relates to apparatus for testing air and gases by means of the variation in color of a liquid reagent.

A primary object of my invention is to 20 provide apparatus of this type in which a small quantity of the liquid reagent is automatically obtained at definite intervals of time from a supply of the reagent and automatically supplied to one or more testing 25 bodies, down which it trickles and changes in color corresponding to the nature of the gas or air to be tested for the time being.

Some illustrative embodiments of my invention are represented by way of example 30 in the accompanying drawing, wherein:—

Figure 1 is a vertical sectional elevation showing one form of apparatus, and Figs. 2 and 3 are like views showing modifications.

Referring firstly to Fig. 1, e^1 designates 35 a receptacle containing the liquid reagent e , whose level can be kept approximately constant. A tube leads from the receptacle e^1 to the bowl e^2 , over which is suspended a flexible body g , *e. g.* a tape or ribbon, in the 40 path of a scoop d which is connected by a rod c with a crank b revoluble about an axle a driven by clockwork U .

A number of basins i are arranged in a 45 row at certain equal distances apart below the body g . A thread $f^1, f^2, f^3, f^4, f^5, f^6$ is attached to each basin, respectively, and depends therefrom to the next lower basin. These basins i may all be secured on a frame h , or the top one may be attached to the 50 bowl e^2 .

This form of my apparatus works as follows:—The liquid reagent e may be a soda solution colored with phenolphthalein. When the axle a is driven by the clockwork 55 U the scoop d dips at certain intervals into the bowl e^2 and when rising takes liquid re-

agent out of the same and delivers it to the ribbon g . The same flows from this in drops t into the first basin i , is taken up by the thread f^1 and drops therefrom into the 60 basin f^2 , and so on.

If the apparatus is in pure atmospheric air the reagent retains its original violet coloration until it arrives at the lowest drop t , whereas in the impure air of a room, 65 on the contrary, one piece of thread after another from below upward loses its coloration, as the impurification of the air increases, owing to carbon dioxid and other impurities, so that the air is exceedingly bad 70 if the top piece of thread f^1 appears violet-red.

Instead of a number of pieces of thread $f^1, f^2, \dots$ one single thread extending from the top basin i to the lowest drop t may be 75 employed. The scoop d may be moved either by an oscillating or by a rotating arm b .

Referring now to Fig. 2, the axle a rotates a disk b once an hour by means of clock-work U . This disk has on its periphery a 80 number of teeth b^4 adapted to engage with the arm b^1 of an angle lever b , b^1 which can rock about the fulcrum b^2 . Each tooth b^4 when engaging with the arm b^1 lifts the scoop d out of the reagent in the bowl e^2 85 and then allows it to dip into the reagent again.

In the modification shown in Fig. 3, the clockwork again drives the axle a and toothed disk b^3 , whose teeth b^4 rock the 90 angle lever b , b^1 around its fulcrum b^2 so that the rod c is raised and allowed to fall by each tooth and thereby causes the scoop or spoon d alternately to be lifted out of and immersed into the liquid reagent e in the 95 bowl e^2 . The spoon d rocks about a pivot d^1 and is driven by means of a pin d^2 and the rod c attached to the latter. When the spoon is immersed and rocked it scoops up a small quantity of the reagent and delivers 100 it to the body or ribbon g .

I claim—

1. Apparatus for testing air and gases, comprising in combination, a vessel containing a liquid reagent, a bowl containing 105 liquid reagent connected therewith, a scoop, means for immersing the scoop into and lifting the same out of liquid in the bowl, and a flexible body arranged in the path of the rising scoop for receiving and delivering 110 in drops the liquid raised by the scoop from the bowl.

2. Apparatus for testing air and gases, comprising in combination, a vessel containing a liquid reagent, a bowl containing liquid reagent connected therewith, a plurality of superposed basins arranged adjacent said bowl, a thread depending from each basin to the basin next below and from the lowest basin, a scoop, mechanism comprising a clockwork-driven crank and a rod 10 carrying the scoop pivoted thereto for immersing the scoop into and lifting the same out of the liquid in the bowl, and a ribbon arranged in the path of the rising scoop and leading to the top basin for receiving and 15 delivering in drops the liquid raised by the scoop from the bowl.

3. Apparatus for testing air and gases, comprising in combination, a vessel containing a liquid reagent, a bowl containing liquid reagent connected therewith, a scoop, 20 clockwork-driven mechanism for immersing the scoop into and lifting the same out of liquid in the bowl, a flexible ribbon-like body arranged in the path of the rising scoop for receiving and delivering in drops the liquid raised by the scoop from the bowl, and a thread arranged under the bottom end 25 of said body for receiving the drops of liquid.

30 4. Apparatus for testing air and gases

comprising in combination a means for containing a liquid reagent, means adjacent said liquid reagent containing means to receive small quantities of the reagent, means to regularly and periodically deliver small 35 quantities of the reagent from the containing means to the receiving means, and a series of members forming a long guiding path for the reagent to which said receiving means delivers and by which the reagent is 40 exposed to the action of the air or gas and dropped from one to the other of said members.

5. Apparatus for testing air and gases comprising in combination a bowl for containing liquid reagent, means to maintain the level thereof constant, a flexible ribbon adjacent said bowl, means to periodically deliver small quantities of reagent from the bowl to the ribbon and means forming a 45 50 long vertical path to which said ribbon delivers the reagent.

In testimony that I claim the foregoing as my invention, I have signed my name in presence of two subscribing witnesses.

MAX ARNDT.
